US00D832671S

(12) **United States Design Patent** (10) Patent No.: **US D832,671 S**
(45) Date of Patent: ** *Nov. 6, 2018

(54) **ANCHOR POINT CLAMP**(71) Applicant: **Cequent Consumer Products, Inc.**,
Solon, OH (US)(72) Inventors: **Dhananjay Gangakhedkar**, Twinsburg,
OH (US); **Matthew Romanak**, Garfield
Heights, OH (US); **Curt Geidman**,
Strongsville, OH (US)(73) Assignee: **Cequent Performance Products, Inc.**,
Bloomfield Hills, MI (US)

(*) Notice: This patent is subject to a terminal disclaimer.

(**) Term: **14 Years**(21) Appl. No.: **29/486,870**(22) Filed: **Apr. 3, 2014****Related U.S. Application Data**(62) Division of application No. 29/404,041, filed on Oct.
14, 2011, now Pat. No. Des. 705,029.(51) **LOC (11) Cl. .... 08-05**(52) **U.S. Cl. USPC .....** **D8/72****Field of Classification Search**USPC D8/71-74, 394, 59; 248/62, 63, 72, 74.1,

OTHER PUBLICATIONS The Hooker—A Universal Truck Bed Hook, <http://thehookerbiz/>, p.
1; Feb. 25, 2010.*Primary Examiner* — David Muller(74) *Attorney, Agent, or Firm* — McDonald Hopkins LLC**CLAIM**The ornamental design of an anchor point clamp, as shown
and described.**DESCRIPTION**FIG. 1 is a rear perspective view of an anchor point clamp
showing our new design;

FIG. 2 is a front perspective view thereof;

FIG. 3 is a rear elevation view thereof;

FIG. 4 is a front elevation view thereof;

FIG. 5 is a first side elevation view thereof;

FIG. 6 is a second side elevation view thereof;

FIG. 7 is a top plan view thereof; and,

FIG. 8 is a bottom plan view thereof.

The features shown in broken lines in the drawing figures
depict environmental subject matter only and form no part of
the claimed design.**1 Claim, 3 Drawing Sheets**(56)
